REGISTERING MECHANISM AND
COMPUTING DEVICE

Kenly C. Bugg, Fort Wayne, Ind.

Application November 24, 1939, Serial No. 305,758

44 Claims. (Cl. 74—283)

This invention pertains to variating or integrating mechanism, and more particularly to a speed variator for computing the price, characteristic of a computing head.

It is an object of this invention to provide variating mechanism for a computing head wherein the driving gears are constantly in mesh and rotate each shaft within the mechanism to cause the selected shaft to operate.

Another object is to provide a variating mechanism wherein the gearing is disposed so that a majority of the gearing is adapted to give an effective one-to-one ratio, i. e., drive at the same speed.

Still another object of the invention is to provide a variator wherein the effective price selection is made by coupling the selected gears to their respective shafts by a vertical coupling, not using the face of said gears, and thereby eliminating the necessity of using gears with thick faces.

Yet another object is to provide a variator wherein all undue wear on the gear faces is eliminated as all the gears rotate, except for zero selection, the gears other than the selected gears operating as idlers.

A different object is to provide a variator wherein the inertia is greatly reduced as it is limited to the selected tier of gears, and a device is attained which runs evenly.

Another different object is to provide a variator wherein selector rings are provided for setting the device, the rings being so constructed and arranged that a ring can only make one selection at a time, yet selection may be easily accomplished as it is done only by a rotative movement, the movement and relation of the parts being such that gears do not have to be felt for, as where the faces of gears must be meshed.

Still a different object of the invention is to provide a variator wherein the casing at least partly comprises the operative selector members or rings.

Yet a different object is to provide a variator having selector mechanism for the various price steps which are of the same size and fashioned so that simplified daily price means (or price synchronizing means) may be used.

Still another different object is to provide a variator wherein the position of the price driving members can be had at a plurality of points, and also the gallons or amount take-off may be from a plurality of points.

Yet another different object is to provide a variator wherein the gears are arranged in tiers, 55

making it possible to place the shafting in a circle common to all tiers, thereby permitting certain shafts to be carried through all tiers, and allowing operative engagement of the selecting rings with the clutch members of the gears, and also a convenient arrangement of the differential.

Another object is to provide a variator having selecting rings for ready selection of the price at which the device is to be set, which rings, gear and shaft connecting mechanism eliminate additional elements, such as springs, to disengage the gear and shaft connections as the disconnection and connection is accomplished positively.

Another object is to provide variator mechanism having connecting mechanism which is self-retaining, is operative to urge the gear and shaft connecting mechanism into operative position, and positively retains such mechanism in operative position after full connection.

Another object is to provide a variator mechanism having setting means forming, in effect, part of the housing whereby the computing means is effectively housed so that the gearing is protected and it is impossible to tamper with any mechanism to cheat the visible set price.

Another object is to provide variating means which will only compute at the figures at which it is set.

Another object is to provide variator mechanism having the operating shafts circularly arranged about a centrally disposed differential permitting the use of circular selecting means, this being made possible by carrying certain shafts through the tiers of the mechanism, and providing gearing in such a way as to properly compound certain of the gearing.

Another object is to provide a variator so constructed and arranged that stamped gears can be readily used, permitting the use of gears made inexpensively and lightly, this being made possible by continuous meshing of the gearing; because where gears must be moved into engagement with other gears for selective operation, they must have wide faces to prevent mutilation of the teeth while being engaged and to insure engagement, and such a gear must be made by a relatively expensive process as it cannot be stamped relatively cheaply.

Another object is to provide a variator wherein the arrangement is such as to reduce the number of bearings to a minimum.

Another object is to provide a variator which is small, compact, strong, and so constructed and arranged as to be easily and readily assembled.

thereby permitting the use of simple and inexpensive tools and fixtures necessary for assembly.

Another object is to provide a variator so constructed and arranged that an oil reservoir is provided for lubrication of the entire device.

Another object is to provide a variator having retaining means for the entire device.

Another object is to provide a variator mechanism wherein the setting means includes rotatable selecting members which are maintained in rotative position by means of the mechanism operated thereby.

Another object is to provide variating means having a plurality of ranges, each being adapted to be set by movable means, as pushbuttons, located in one plane.

Another object is to provide variating means which can be set only in accordance with the visible indications on the variating setting indicator or price synchronizing means.

Another object is to provide variating means for the computing head of a liquid dispensing apparatus which fulfills all the herein recited and apparent objects.

With these and various other objects in view, the invention may consist of certain novel features of construction and operation as will be more fully described and particularly pointed out in the specification, drawings and claims appended hereto.

In the drawings, which illustrate embodiments of the device, and wherein like reference characters are used to designate like parts—

Figure 1 is an enlarged top plan view of the tens portion of one form of variator embodying the invention, the same being taken substantially in the plane as indicated by the line 1—1 of Figure 7, and showing the disposition of the parts where that portion of the variator is set for twenty cents;

Variating mechanism—Figures 1 to 28 inclusive

Referring first of all more particularly to the form of variator illustrated in Figures 1 to 24 inclusive, said variator consists essentially of the spaced supporting plates 50, 52, 54 and 56, the space between the plates 50 and 52 being closed by the ring 58, thus forming a lubricant reservoir. The cover plate 60 is provided to complete the housing, and the plates are suitably secured together by means of the spaced securing rods 62, the opposite sides of the cover plate 60 being cut away as indicated at 64 to permit setting of the device, as will more clearly hereinafter appear. Inasmuch as common securing means is used for the entire height of the device, suitable spacing bearing sleeves 66 are disposed between the tiers formed by the plates to form a rigid assembly and correctly space said tiers.

Driving gears

In this form of the device the drive shaft 68 extends into the space between the plates 54 and 52, and is provided with the cams 63 (Figure 13) having cooperative engagement with the sliding pawl 65 for preventing reverse rotation of the drive shaft, said pawls being positioned by the straps 67 fastened to the plate 50, it being seen that the normal rotation of the drive shaft 68 is clockwise in top plan. The shaft 68 is provided with the twenty-tooth gear 66 which meshes with the forty-tooth gear 70 non-rotatably mounted on the shaft 72. The gear 70 meshes with the forty-tooth gear 74 non-rotatably mounted on the shaft 76. The shaft 72 is also provided with the forty-two-tooth gear 78 non-rotatably mounted thereon and meshing with the forty-two-tooth gear 80 rotatably mounted on the shaft 84, the gear 80 being provided with the thirty-two-tooth gear 86 also rotatably mounted on the shaft 84, and rotating with the gear 80. The forty-eight-tooth gear 88 is non-rotatably mounted on the shaft 84 and meshes with the sixteen-tooth gear 90 mounted on the shaft 92. The shaft 92 is also provided with the thirty-two-tooth gear 94 meshing with the gear 86, and said shaft is provided with the twenty-eight-tooth gear 96 meshing with the twenty-eight-tooth gear 98 non-rotatably mounted on the shaft 100. The shaft 100 is provided with the thirty-two-tooth gear 102 non-rotatably mounted thereon, said gear meshing with the thirty-two-tooth gear 104 non-rotatably mounted on the shaft 106. The shaft 106 is provided with the thirty-six-tooth gear 108 non-rotatably mounted thereon, said gear meshing with the thirty-six-tooth gear 110 non-rotatably mounted on the shaft 112.

The shaft 112 is provided with the forty-tooth

gear 114 non-rotatably mounted thereon and meshing with the forty-two-tooth gear 116 non-rotatably mounted on the shaft 118. The shaft 118 is provided with the forty-four-tooth gear 120 non-rotatably mounted thereon, said gear meshing with the forty-four tooth gear 122 non-rotatably mounted on the shaft 124. The shaft 124 is provided with a forty-eight-tooth gear 126 non-rotatably mounted thereon, and meshing with the forty-eight-tooth gear 128 non-rotatably mounted on the shaft 130. The shaft 130 is provided with a sixty-eight-tooth gear 132 non-rotatably mounted thereon, and meshing with the sixty-eight-tooth gear 134 non-rotatably mounted on the shaft 136. In order to conveniently mount the various gears on the shafts, the shafts are preferably made of substantially square section, the corners being cut off, however, so that where the gears are made rotatable the shafts can be received in the circular apertures provided in the gear for permitting the rotative mounting.

While the shaft 68 has been shown as driving the shaft 72 through the gearing, it is of course appreciated that any of the shafts 76, 84, 92, 100, 106, 112, 118, 124, 130 or 136 may be used as the drive shaft.

Fraction selecting mechanism

The fractions selecting mechanism, illustrated in Figures 5, 7, 19, 22 and 25 includes selective computing gears, such as shown in Figure 5, disposed between the plates 52 and 54 and within the fractions setting ring 140. The fractions selecting ring 140 is provided with the upper peripheral flange 142, said flange being provided with the spaced apertures 144. Said fraction selecting ring is calibrated to be read in tenths, and one-quarter and three-quarters of a cent, such as shown at the stations 146, the calibrations being indicated at said stations. Corresponding to said stations locking recesses or indentations 148 are provided.

It will also be noted that there is a locking passageway 150 through said ring 140 corresponding to the zero station. Said stations at which the visible numerals are placed, as well as the recesses and the passageway, are provided in the lower flange 152 of said ring, said flange also providing a bearing for the ring on the plate 52. The ring is provided with the inwardly extending clutch operating, or selecting, or carrying flange 154, said flange being interrupted at 156 and 158, downwardly projecting planes or track members 160 and 162 being disposed on each side of the interruption, said track members being similar to the members 326 and 328 (Figures 9 and 10).

The shafts 72, 76, 84, 92, 100, 106, 112, 118, 124, 130 and 136 extend upwardly through the plate 52 and within said ring, said shafts being provided, respectively, with the slideable coupling, or clutch members, or sleeves 164 non-rotatably mounted on said shafts, the coupling members being provided with the head 166 beveled as at 168, the head being larger than the sleeves and being adapted to be carried on the flange 154 unless the flange has been rotated by the ring 140 to permit the member 164 to move downwardly between the interrupted portions 156 and 158. When the heads 166 of the coupling members are supported on the flange 154, the clutches are open, but where a clutch sleeve is disposed between the interrupted portions 156 and 158, that clutch sleeve is operative, all as more particularly hereinafter described.

The members 164 are provided with the depending fingers or crown 170 adapted to be received by the complementary crown or upstanding fingers 172 provided on the gears which are rotatably mounted on the respective shafts. In order to retain the selected clutch sleeve 164 in its lowermost or clutched position between the interrupted portions 156 and 158, the retaining lever or member 174 is provided, said member having bevelled sides 175, said lever being similar to the lever 330 (Figures 9 and 10), and having the fixed pivot post 176 extending through and journaled in the flange 154 and being provided with the spaced pins 178 and 180 secured, respectively, to one end of the contractile springs 182 and 184, said springs being secured at the other ends thereof as at 186 and 188 (Figure 11) to the ring.

The shaft 76 is provided with the twenty-tooth gear 190 for the one-quarter cent ($\frac{1}{4}$ ¢) computation, rotatably mounted thereon and provided with the upstanding fingers or crown 172, said gear meshing with the sixty-tooth-gear 192 for the three-quarters cent ($\frac{3}{4}$ ¢) computation, rotatably mounted on the shaft 72. The gear 192 meshes with the twenty-four-tooth gear 194 for the one-tenth cent ($\frac{1}{10}$ ¢) computation, rotatably mounted on the shaft 84, the gear 194 meshing with the forty-tooth-gear 196 for the five-tenths cent ($\frac{5}{10}$ ¢) computation, rotatably mounted on the shaft 92, and said gear 196 meshes with the sixteen-tooth-gear 198 for the two-tenths cent ($\frac{2}{10}$ ¢) computation, rotatably mounted on the shaft 100. The gear 198 meshes with the forty-eight-tooth-gear 200 for the six-tenths cent ($\frac{6}{10}$ ¢) computation, rotatably mounted on the shaft 106, and said gear 200 meshes with the twenty-four-tooth-gear 202 for the three-tenths cent ($\frac{3}{10}$ ¢) computation, rotatably mounted on the shaft 112.

The gear 202 meshes with the fifty-six-tooth-gear 204 for the seven-tenths cent ($\frac{7}{10}$ ¢) computation, rotatably mounted on the shaft 118, said gear 204 meshing with the thirty-two-tooth-gear 206 for the four-tenths cent ($\frac{4}{10}$ ¢) computation, rotatably mounted on the shaft 124. The gear 206 meshes with the sixty-four-tooth-gear 208 for the eight-tenths cent ($\frac{8}{10}$ ¢) computation, rotatably mounted on the shaft 130, and said gear 208 meshes with the seventy-two-tooth-gear 210 for the nine-tenths cent ($\frac{9}{10}$ ¢) computation, rotatably provided on the shaft 136. As already pointed out, each of said gears is provided with the upstanding crowns 172 adapted to receive the corresponding crowns on the respective clutch sleeves 164, non-rotatably mounted on the respective shafts.

Differential mechanism—Figure 12

The gear 210 meshes with the eighty-tooth-gear 212, non-rotatably provided on the hollow shaft 214, said hollow shaft being journaled in the plate 52 extending through and being journaled in the plate 54, said hollow shaft, between the plates 54 and 56, being provided with the ten-tooth-gear 216, non-rotatably mounted thereon.

The sixty-four-tooth-gear 218 is rotatably mounted on the hollow shaft 214, a spacing washer 220 being provided below the gear 218, said gear being provided with the stepped pinions 222 rotatably mounted thereon as at 224. Each stepped pinion 222 consists of the lower twenty-tooth-pinion 226 meshing with the pinion 218, and the upper ten-tooth-pinion 228 meshing with the twenty-tooth-gear 230, non-rotatably mounted

on the shaft 232 which is pivotally received in the hollow shaft 214.

The gear 230 is provided with the hollow sleeve 234 extending upwardly into the space between the plates 56 and 60, being journaled in the plate 56, and said sleeve is provided with the ten-tooth-pinion 236. The spacing washer 238 is provided around the sleeve 234, and the forty-eight-tooth-gear 240 is supported on said washer and rotatably mounted on the sleeve 234. The gear 240 is provided with the compound pinions 242 rotatably mounted thereon at 244, said compound pinions each including the lower twenty-tooth-pinion 246 meshing with the gear 236, and includes the upper ten-tooth-pinion 248 meshing with the gear 250 provided on the sleeve 254. The sleeve 254 is secured to the shaft 256 extending downwardly and journaled in the hollow sleeve 234, and said sleeve 254 is journaled in the cover plate 60 and is provided with the money take-off bevel gear 258.

Units selecting mechanism

The units selecting mechanism such as shown in Figures 3, 7, 18, 21 and 24 includes the selecting ring 260 calibrated, in the embodiment shown, in units of a cent from zero to nine cents, and rotatably mounted between the plates 54 and 56, said ring 260 being essentially similar to the ring 140. The ring 260 is provided with the upper peripheral flange 262 provided with the spaced apertures 263, and is provided with the inwardly projecting clutch operating, or selecting, or carrying flange 264. Said ring 260 is seated on the plate 54 by the lower bearing flange 266.

As in the case of the flange 154, the flange 264 is provided with the spaced downwardly projecting track members 268 and 270 adapted to move the clutch members 272 in engaged or disengaged position. When said members are carried by the flange 264 they are in disengaged position, when disposed between the members 268 and 270 they are in engaged position. Said members include the bevelled head 274, and the spaced downwardly projecting fingers or crowns 276, the members being non-rotatably mounted on their respective shafts.

When the members 272 are in clutch engaging position they have moved downwardly over the members 268 or 270 to a point below the inwardly extending retaining and positioning lever 278. Said lever is similar to the lever 174, and is fixedly mounted on the pivot 280 similar to the pivot 176 extending below the ring and being provided with the spaced pins 178 and 180, such as shown in Figure 10, engaging the springs 182 and 184, said springs being secured at their opposite ends to the ring to retain the lever in its outwardly projecting position. The shafts 72, 84, 92, 100, 106, 112, 118, 124, 130 and 136 are projected upwardly into the space between the plates 54 and 56 and within the ring 260, and a shaft 282 is journaled between said plates 54 and 56 and is provided with the sixty-four-tooth-gear 284 meshing with the gear 218 of the differential. The gear 284 is provided with the twenty-four-tooth-gear 286 meshing with the sixty-tooth-gear 288 rotatably mounted on the shaft 72 and meshing with the twenty-four-tooth-gear 290 of the one cent (1¢) value, said gear being rotatably mounted on the shaft 84.

The gear 290 meshes with the forty-tooth-gear 292 for the five cent (5¢) value, said gear 292 being rotatably mounted on the shaft 92. The

gear 292 meshes with the sixteen-tooth-gear 294 for the two cent (2¢) value, said gear 294 being rotatably mounted on the shaft 100. The gear 294 meshes with the forty-eight-tooth-gear 296 for the six cent (6¢) value, said gear 296 being rotatably mounted on the shaft 106, and said gear 296 meshes with the twenty-four-tooth-gear 298 for the three cent (3¢) value, said gear 298 being rotatably mounted on the shaft 112. The gear 298 meshes with the fifty-six-tooth-gear 300 for the seven cent (7¢) value, said gear 300 being rotatably mounted on the shaft 118, and said gear 300 meshes with the thirty-two-tooth-gear 302 for the four cent (4¢) value, said gear 302 being rotatably mounted on the shaft 124. The gear 302 meshes with the sixty-four-tooth-gear 304 for the eight cent (8¢) value, said gear 304 being rotatably mounted on the shaft 130, and said gear 304 meshes with the seventy-two-tooth-gear 306 for the nine cent (9¢) value, said gear 306 being rotatably mounted on the shaft 136.

The selecting ring 260 is provided with the stations 308 visibly indicating the selected gear or selected price, and is provided with the recesses 310 for receiving the locking means for the ring. In the zero position the ring is provided with the passageway 312 disposed through the flange 260. Each of the gears 290, 292, 294, 296, 298, 300, 302, 304 and 306 are provided with the upwardly extending crowns 314 complementary to the crowns 276, being adapted to receive said crowns when the members 272 are moved to clutch engaging position beneath the lever 278 and between the track members 268 and 270 to connect the selected gear to its respective shaft.

Tens selecting mechanism

The tens selecting mechanism shown in Figures 1, 7, 9, 10, 17, 20 and 23 includes the selecting ring 316 similar to the selecting rings 140 and 260, and disposed between the plate 56 and the cover 60. Said ring 316 is provided with the upper outwardly extending peripheral flange 318 provided with the spaced apertures 320, and said ring is also provided with a depending flange 322 providing a bearing for said ring on the plate 56. As before, the ring is provided with the inwardly extending selecting flange 324 similar to the flanges 154 and 264 having the spaced downwardly projecting track members or sloping portions 326 and 328. Between said track members the retaining lever 330 is disposed, said lever being similar to the levers 174 and 278, and being provided with the fixed pivot 332 extending through and journaled in the flange 324, and being provided with the spaced lugs 178 and 180 (Figure 11) for receiving the springs 182 and 184, said springs being secured at their opposite ends to the under side of said flange.

The sloping portions 326 and 328 are provided to direct the selection of the clutch members 334, said clutch members being similar to the clutch members 272 and 184, having the enlarged bevelled heads 336 and the downwardly projecting crowns 338, said members being non-rotatably mounted on their respective shafts. As before, the depending flange 322 is provided with the stations 340 for visibly indicating the price selection or the selection of the gears, and is provided with the recesses 342 (similar to the recesses 148 and 310) corresponding to the selected gears, the passageway 344 being provided

corresponding to the zero indication. A shaft 346 is journaled between the plate 56 and the cover 60, said shaft being provided with the forty-tooth-gear 348 meshing with the gear 240 of the differential, and the gear 348 is provided with the sixteen-tooth-gear 350 meshing with the sixty-four-tooth-gear 352 for the forty cent (40¢) selection, the gear 352 being rotatably mounted on the shaft 130 which projects through the plate 56 and is journaled in the cover 60. The gear 352 meshes with the thirty-two-tooth-gear 354 corresponding to the twenty cent (20¢) selection, said gear being rotatably mounted on the shaft 124 and meshing with the fifty-six-tooth-gear 356 rotatably mounted on the shaft 118, the shafts 124 and 118 projecting through the plate 56 and being journaled in the cover 60.

The gear 356 meshes with the twenty-four-tooth-gear 358 rotatably mounted on the shaft 112, and said gear 358 meshes with the forty-eight-tooth-gear 360 corresponding to the thirty cent (30¢) selection, said gear 360 being rotatably mounted on the shaft 106, the shafts 112 and 106 projecting through the plate 56 and being journaled in the cover 60. The gear 360 meshes with the sixteen-tooth-gear 362 corresponding to the ten cent (10¢) selection, said gear 362 being rotatably mounted on the shaft 100 and meshing with the forty-tooth-gear 364 provided for locking the gear train, said gear 364 being rotatably mounted on the shaft 92, the shafts 100 and 92 projecting through the plate 56 and being journaled in the cover 60.

In this device any of the upwardly extending through-shafts 92, 100, 106, 112, 118, 124 or 130 may be projected through the cover 60 for driving an amount counter or registering mechanism. In this particular embodiment the shaft 118 is shown as projected through said cover, said shaft being provided with the bevel gear 366 for connection to the counter.

Locks for selecting rings

In order to lock the locking rings in their selected positions to prevent accidental turning, the plates 52, 54 and 56 are each provided with locking means such as the locking button and plunger 368, which as shown are conveniently disposed in a vertical plane. Only one locking plunger is shown in Figures 2 and 4, it being understood that the locking plungers are all alike. In this instance the locking plunger is illustrated in different positions for locking the adjacent selecting ring, and for the purpose of this description the selecting ring 316 is illustrated, the ring being in its twenty cent (20¢) position in Figure 2, and in its zero position as shown in Figure 4.

The locking plunger 368 is provided with the push button 370 for convenient manipulation, said button being urged toward its locking position by means of the spring 372, the plunger being provided with the depending pin 374 adapted to be received in the selected recess 342, in which case the inner locking tooth or projection 376 is spaced from the gear 364 so that the selected gear 354 is operative to rotate the gear train, including gear 364, as idlers, the motion of the gear 354 being transmitted to the differential. When, however, the zero position is selected, the pin 374 is urged into the passageway 344 of the ring 316 by the spring 372, in which case the locking projection 376 engages the gear 364 as shown in Figure 4, thereby pre-

venting rotation of the entire train of gears in that particular tier. Thus, where any ring is set to permit the projection to be received in either the passageway 344, 312 or 150, the entire train of gears in that tier (or within that ring) is rendered inoperative so that either the tens, units or fractions may be set for zero computation. Of course, if they all are set for the zero computation there will only be a direct drive of the shaft 72 and consequently the gear 366.

Price synchronizing mechanism

In order to show the setting of the variator, price synchronizing means or daily price means is used, one form of this means being illustrated in Figures 14, 15 and 16. This price synchronizing means comprises the shafts 378, 380 and 382, corresponding to the tens, units and fractions, said shafts being disposed on one side of the variator and being secured to the support 384. On the opposite side of the variator the support 386 is provided having the shafts 388, 390 and 392 corresponding to the tens, units and fractions, and the supports may be conveniently provided with the windows 394 for conveniently viewing the numeral indicating the position of the corresponding selecting ring.

Each of the shafts is provided with a numeral wheel 396 pivoted to said shafts and urged toward the zero position by means of the spring 398. Said numeral wheels are each provided with the tracks 400 for receiving the chains 402, 404 and 406 of the respective selecting rings 316, 260 and 140, the chains being anchored at opposite ends to the corresponding numeral wheels of the supports 384 and 386. It will be noted that the selecting ring 140 is substantially in the plane of the track 400, but that the other selecting rings are diagonally disposed. Slots are provided through the supports for accommodating such chains, and suitable guide rollers 408 and 410 are provided where an abrupt change in direction is necessary. It will thus be seen that a rotation of the selecting rings will cause the chains to be moved, as the chains are of the ball and link embodiment, the balls being received in the notches 412 in the respective selecting rings below the apertures 320, 263 and 144, the notches in effect being a continuation of said apertures.

In order to remotely control the locking means for the selecting rings a slideable link 414 may be provided for each button 370, said links being supported at their outer ends in the slots 416 of the plate 418 disposed on the support 386, and said links are provided with the levers 420 pivoted to the respective levers and having the cams 422 abutting the plate 418 for permitting movement and positioning of the links 414.

Inasmuch as the daily price numeral wheels are spring-loaded and the chains are anchored at one end to the tracks 400, it is desirable to provide means for limiting the rotatable movement of the selecting rings. To this end the supports 52, 54 and 56 are provided with the spring-pressed pawls 424 and 426 pivoted to said plates as at 428 and 430, said pawls being oppositely faced and being adapted to engage limiting depressions 432 and 434, provided in the selecting rings, said depressions being so located that in the zero position the pawl 424 engages the recess so that the setting of the rings can only be had in one direction, i. e., clockwise as viewed in Figures 1, 3 and 5. The pawl 426 is slightly longer than the distance between the pivot 430 and the depression 434 to permit the setting of the

rings in a clockwise direction, but the depression is so located that the pawl 426 will engage in such depression 434 to prevent the selecting rings from being moved too far.

Referring now to the form of price synchronizing mechanism illustrated in Figures 26 and 27, the price synchronizing means shown is adapted for use with the variator shown in Figures 1 to 25 inclusive, said price synchronizing means including the horizontal shaft 436 disposed on each side of the variator and suitably supported as in supports similar to those shown at 384 and 386. The tens numeral wheel 438, the units numeral wheel 440, and the fractions numeral wheel 442 are rotatably mounted on the shaft 436 and suitably positioned thereon, each of said numeral wheels being provided with the chain track 444 for receiving the chains 446, 448 and 450, said chains engaging and being moved, respectively, by the tens selecting ring 316, the units selecting ring 260, and the fractions selecting ring 140, the ends of said chains being anchored to the respective numeral wheels. Where an abrupt change of direction is necessary, said chains pass over suitable rollers 452, 454, 456 and 458, and may extend through suitable slots 460 in the side walls 462 of the cover 60. As before, the numeral wheels may be spring-loaded, tending to return said wheels to the zero position, a suitable casing (not shown) being provided having windows for viewing the numerals of the numeral wheels. It will thus be seen that the rotation of the numeral wheels causes movement of the chains to cause the selected numeral to appear in the proper window to indicate the position of said selecting rings, the numeral wheels being calibrated to correspond to the calibrations of the corresponding selecting rings.

In the modification illustrated in Figure 28, a form of price synchronizer is illustrated permitting the elimination of the pawls 424 and 426, that is, the arrangement is such that the selecting rings 316, 260 and 140 may be rotated in either a counterclockwise direction, or a clockwise direction for setting the device. In this case the arrangement of the numeral wheels is similar to that shown in Figure 16, the tens numeral wheels 464 and 466 being pivotally mounted as at 468 and 470 on opposite sides of the variator, the units numeral wheels 472 and 474 being disposed on opposite sides of the variator and pivoted as at 476 and 478, and the fractions numeral wheels 480 and 484 being disposed on opposite sides of the variator and pivoted as at 486 and 488. In this case the tracks for receiving the chains corresponding to the tracks 400 are grooved, as are the selecting rings such as shown at 412 in Figure 3. The chains 490, 492 and 494 for the tens, units and fractions daily price indicating wheels are continuous and pass around their respective price selecting rings 316, 260 and 140, respectively, and the tracks of the numeral wheels, and where said chains make an abrupt turn, guide rollers 496, 498 and 500 are provided. Thus, in this form of the device movement of the preselecting rings in either a clockwise or a counterclockwise direction effects corresponding movement of the corresponding daily price wheel.

Operation of the variating mechanism

In the operation of the form of variating mechanism illustrated in Figures 1 to 28 inclusive, assuming that the selecting rings 316, 260 and 140 are in their respective zero positions, the price synchronizing wheels will of course be set

at zero, and the pins 374 of the locking mechanism will be received in the passageways 344, 312 and 150, respectively, as illustrated in Figure 4. The projection 376 of the plungers 368 will be in engagement with the adjacent gears 364, 292 and 196, locking the gear trains in the respective tiers, and the pawls 424 will be in engagement with the notches 432. In this position all of the clutch members on the various shafts will be disengaged, that is, the heads of the clutch members 334, 272 and 164 in the respective tiers will be carried by the adjacent flanges 324, 284 and 154.

If it is desired to set the variator mechanism for twenty-three and two-tenths cents (23.2¢), for example, the tens selecting ring 316 may be unlocked by moving the plunger 368 outwardly to disengage the pin 374 from the passageway 344. The ring 316 can then be rotated in a clockwise direction, causing the chain 402 to move the price synchronizer wheels 386 to a position to indicate "2," that is, twenty cents (20¢). At this position the twenty cent (20¢) numeral will appear at its proper station, and the plunger 368 can be released to permit the pin 374 to engage the proper recess 342 to prevent accidental movement of the selecting ring. Moving to this position, the clutch member 334 on the shaft 124 will be moved between the spaced track members 326 and 328, causing the shaft 124 to be connected to the gear 354. The drive from the shaft 66 will then be through the train of gears in the driving tier (Figure 6) to the shaft 124, and thence through the gears 354, 352 and 348 to the gear 240 of the differential. It will be seen that the lever 330 will have moved over the top of the clutch member 334 to hold it in clutch engaging position.

In order to set up the three cent (3¢) portion of the selected price, the selecting ring 260 is unlocked by moving its plunger 368 outwardly. The ring can then be rotated in a clockwise direction, causing the chain 404 to move the middle daily price wheels to the numeral "3," at which time the plunger 368 is released and the projection 374 is received in the corresponding recess 310 of the selecting ring 260. When the selection is made, the clutch member 272 of the shaft 112 will have been moved to clutch engaging position beneath the lever 278 connecting the shaft 112 to the gear 298. Thus the drive from the shaft 66 will be through the gear train of the driving gears, shown in Figure 6, to the shaft 112 and to the gear 298, and from the gear 298 through the gear train 296, 294, 292, 290, 288, and compound 286 and 284 to the gear 218 of the differential.

In setting up the two-tenths cent ($\frac{2}{10}$ ¢) portion of the selected price the plunger 368 of the fractions tier will be moved outwardly to release the projection 374 from the passageway 150 of the selecting ring 140. The ring can then be rotated in a clockwise direction causing the chain 406 to move the fractions daily price wheels to show two-tenths cent ($\frac{2}{10}$ ¢) in the window, at which time the plunger 368 can be released and the projection 374 will be received in the recess 148 corresponding to the two-tenths ($\frac{2}{10}$) position. In rotating the ring to the two-tenths ($\frac{2}{10}$) position the clutch member 164 on the shaft 100 will be moved between the spaced portions 162 and 160 and beneath the lever 174 to clutch engaged position so that the drive from the shaft 66 will be through the gear train of the driving gears, shown in Figure 6, to the shaft 100. The drive from the shaft 100 will then be transmitted

through the gears 198, 200, 202, 204, 206, 208, and 210 to the gear 212 of the differential.

The motion from the tiers of price selecting gearing is added through the differential to the gear 258 where it can be transmitted to suitable registering mechanism. As already indicated, the other characteristic of motion is transmitted from the shaft 66 to the gear 366 to other suitable registering mechanism. With this form of mechanism it is possible to provide a computing head, for example, for devices, one of the best known of which is a computing type of pump wherein the meter can be directly connected to the shaft 66 to drive said shaft, the registering mechanism connected to the gear 366 showing the number of gallons dispensed, or passing through the meter, while the registering mechanism connected to the gear 258 will show the computed cost of the liquid passing through the meter, in accordance with the setting of the device.

Variating mechanism—Figures 30 to 39 incl.—Driving gears

In the variating mechanism illustrated in Figures 30 to 39 inclusive, the supports 1006, 1008, 1010, 1012 and 1014 are rigidly secured together and the drive shaft 1016 is provided which may be connected as at 1018 to suitable driving means such as a meter shaft in the case of a liquid dispensing apparatus. The shaft 1016 is substantially square in section and is provided with the gear 1020 non-rotatably mounted thereon which, in the embodiment shown, has 68 teeth. The gear 1020 meshes with the gear 1022, also having sixty-eight teeth and non-rotatably mounted on the substantially square-sectioned shaft 1024. The gear 1026, shown as having sixty-six teeth, is non-rotatably mounted on the shaft 1024 and meshes with the gear 1028, shown as having sixty-six teeth and non-rotatably mounted on the square shaft 1030.

The shaft 1016 is provided with the sixty-tooth-gear 1032 non-rotatably mounted thereon, meshing with the sixty-tooth-gear 1034 non-rotatably mounted on the square shaft 1036, the shaft 1036 being provided with the fifty-two-tooth-gear 1038 non-rotatably mounted thereon, meshing with the fifty-two-tooth-gear 1040 non-rotatably mounted on the square shaft 1042. The forty-four-tooth-gear 1044 is non-rotatably mounted on the shaft 1042 and meshes with the forty-four-tooth-gear 1046 non-rotatably mounted on the square shaft 1048. The shaft 1048 is provided with the thirty-six-tooth-gear 1050 non-rotatably mounted on said shaft and meshing with the thirty-six-tooth-gear 1052 non-rotatably mounted on the square shaft 1054. The shaft 1054 is provided with the twenty-eight-tooth-gear 1056 non-rotatably mounted thereon and meshing with the twenty-eight-tooth-gear 1058 non-rotatably mounted on the square shaft 1060. The shaft 1060 is provided with the sixteen-tooth-gear 1062 non-rotatably mounted thereon and meshing with the twenty-four-tooth-gear 1064 pivoted as at 1066 between the plates 1006 and 1008. The twenty-four-tooth-gear 1064 meshes with the twenty-four-tooth-gear 1068 pivotally mounted as at 1070, said gear 1068 meshing with the twenty-four-tooth-gear 1072 non-rotatably mounted on the square shaft 1074. The gear 1068 meshes with the sixteen-tooth-gear 1076 non-rotatably mounted on the shaft 1078, said shaft being provided with the eight-tooth-gear 1080 and the

twenty-tooth-gear 1082. The gear 1080 meshes with the twenty-four-tooth-gear 1084 non-rotatably mounted on the square shaft 1086.

The gear 1082 meshes with the twenty-four-tooth-gear 1088 non-rotatably mounted on the shaft 1090, and the gear 1088 meshes with the twenty-four-tooth-gear 1092 non-rotatably mounted on the square shaft 1094. The shaft 1016 extends upwardly through the plates 1008, 1010, 1012 and is journaled in the plate 1014, as are the shafts 1038, 1042, 1048, 1054, 1060 and 1074. Said shafts and the shafts 1024 and 1084 extend through the plates 1008 and 1010, and are journaled in the plate 1012. The shafts 1030, 1024, 1016, 1036, 1042, 1048, 1054, 1060, 1074, 1088 and 1094 extend through the plate 1008, and the shafts 1030 and 1094 are journaled in the plate 1010.

Fraction selecting mechanism

In the fractions bank of wheels, shown in Figure 39, the shaft 1024 is provided with the seventy-two-tooth-gear 1096 meshing with the sixty-tooth-gear 1098 rotatably mounted on the shaft 1030 and meshing with the thirty-two-tooth-idler-gear 1100, which in turn meshes with the eighty-tooth-gear 1102 rotatably mounted on the shaft 1104. The gear 1096 meshes with the sixty-four-tooth-gear 1106 rotatably mounted on the shaft 1016, and said gear 1106 meshes with the fifty-six-tooth-gear 1108 rotatably mounted on the shaft 1038.

The gear 1108 meshes with the forty-eight-tooth-gear 1110 rotatably mounted on the shaft 1042, and said gear meshes with the forty-tooth-gear 1112 rotatably mounted on the shaft 1048. The gear 1112 meshes with the thirty-two-tooth-gear 1114 rotatably mounted on the shaft 1054, and said gear meshes with the twenty-four-tooth-gear 1116 rotatably mounted on the shaft 1060. The gear 1116 meshes with the twenty-four-tooth-gear 1118, and said gear meshes with the twenty-four-tooth-gear 1120, which meshes with the gear 1122, said gears being rotatably mounted on the shafts 1074, 1086 and 1094. The spring-pressed pawl 1124 is pivoted as at 1126 and is normally urged toward disengaging position with respect to the gear 1122.

Units selecting mechanism

In the units bank of wheels, shown in Figure 38, the seventy-two-tooth-gear 1128 is rotatably mounted on the shaft 1024, and meshes with the sixty-four-tooth-gear 1130 rotatably mounted on the shaft 1016. The gear 1130 meshes with the fifty-six-tooth-gear 1132 rotatably mounted on the shaft 1038, and said gear meshes with the forty-eight-tooth-gear 1134 rotatably mounted on the shaft 1042. The gear 1134 meshes with the forty-tooth-gear 1136 rotatably mounted on the shaft 1048, and said gear meshes with the thirty-two-tooth-gear 1138 rotatably mounted on the shaft 1054.

The gear 1138 meshes with the twenty-four-tooth-gear 1140 rotatably mounted on the shaft 1060, and said gear meshes with the twenty-four-tooth-gear 1142 rotatably mounted on the shaft 1074. The gear 1142 meshes with the twenty-four-tooth-gear 1144, rotatably mounted on the shaft 1086, and the spring-pressed pawl 1146 is pivotally mounted as at 1148 adjacent the gear 1144, being normally urged to disengaged position with respect to said gear. The gear 1138 meshes with the eighteen-tooth pinion 1150 pivotally mounted on the shaft 1152, 75

and said pinion is non-rotatably provided with the forty-eight-tooth-gear 1154. The gear 1154 meshes with the sixty-four-tooth-gear 1156 rotatably mounted with respect to the shaft 1152.

Tens selecting mechanism

Referring now to the tens banks of wheels shown in Figure 37, the shaft 1016 is provided with the 64-tooth-gear 1168 rotatably mounted thereon and meshing with the fifty-six-tooth-gear 1160 rotatably mounted on the shaft 1036. The gear 1160 meshes with the forty-eight-tooth-gear 1162 rotatably mounted on the shaft 1042, and said gear meshes with the forty-tooth-gear 1164 rotatably mounted on the shaft 1048. The gear 1164 meshes with the thirty-two-tooth-gear 1166 rotatably mounted on the shaft 1054, and said gear meshes with the twenty-four-tooth-gear 1168 rotatably mounted on the shaft 1060. The gear 1168 meshes with the twenty-four-tooth-gear 1170 rotatably mounted on the shaft 1074, and the spring-pressed pawl 1172 is pivotally mounted as at 1174 and normally urged to disengaging position with respect to the gear 1170. The gear 1158 meshes with the eighteen-tooth-pinion 1178 rotatably mounted on the shaft 1178, and said pinion is non-rotatably provided with the forty-five-tooth-gear 1180 meshing with the forty-eight-tooth-gear 1182 rotatably mounted with respect to the shaft 1104.

Differential mechanism—Figure 33

Referring now to the differential illustrated in Figure 33, as has already been described, the eighty-tooth-gear 1102 is rotatably mounted with respect to the shaft 1104, said gear having an upwardly extending portion provided with the bearing 1184 on which the sixty-four-tooth-gear 1156 is rotatably mounted. The gear 1156 is provided with the twenty-tooth-pinion 1186 meshing with the ten-tooth-gear 1188 provided adjacent the bearing 1184. The pinion 1186 is pivotally mounted as at 1190 on the gear 1156 and is provided with the ten-tooth-gear 1192 meshing with the twenty-tooth-gear 1194 rotatably mounted on the shaft 1104. The gear 1194 has an upwardly extending portion 1196 provided with the bearing 1198 on which the forty-eight-tooth-gear 1182 is rotatably mounted.

The twenty-tooth-pinion 1200 is pivotally mounted as at 1202 to the gear 1182, and meshes with the ten-tooth-gear 1204 provided on the portion 1195. The pinion 1200 is provided with the ten-tooth-gear 1206 meshing with the twenty-tooth-gear 1208 of the thimble 1210, said thimble being rotatably mounted on the shaft 1104 and being provided with the ten-tooth driving gear 1212 adapted to drive the twenty-five-tooth-gears 74 or 900 of the distributors shown in Figure 1 or 14 of application Serial No. 305,757, filed November 24, 1939, or other suitable registering mechanism.

In the embodiment shown, the amount or gallons take-off shaft is shown as the shaft 1016 which is provided with the ten-tooth-gear 1213 adapted to drive the forty-tooth-gears 62 or 902 of the distributors shown in Figure 1 or 14, of said application Serial No. 305,757, or other suitable registering mechanism.

Operation

In order to set the variator to compute at a selected unit price, each bank of selecting wheels is provided with selecting means and an inter-

lock therefor. The tenths selecting means, as illustrated in Figures 32 and 39, includes the zero slide or key 1214, the one-fourth cent (1/4¢) key 1216, the one-tenth (1/10) to nine-tenths (9/10) cent selecting keys 1218, 1220, 1222, 1224, 1226, 1228, 1230, 1232, 1234, and the three-fourths cent (3/4¢) key 1236. An interlocking member 1238 is slidably mounted adjacent the upstanding ends of said keys between the guides 1240.

The units keys 1242 to 1260, respectively (Figures 32 and 38), are ten in number, from 0 to 9, calibrated in increments of one cent, and the locking bar 1262 is slidably mounted adjacent the upturned ends of said keys and guided by means of the spaced members 1264.

The tens keys 1266, 1268, 1270, 1272, 1274 (Figures 32 and 37) are five in number (in the embodiment shown), being adapted to select amounts of 0, 10¢, 20¢, 30¢ and 40¢, and the locking bar 1276 is slidably mounted adjacent the upturned ends of said keys, being guided by the space guides 1278.

The locking bars 1238, 1262 and 1276 are provided with the bayonet slots 1280, 1282 and 1284 adapted to receive the upturned ends of the keys in the full slot position when the selected keys are moved inwardly a sufficient distance to make the proper selection. In order to make the proper selection, the ends of the keys are offset upwardly in side elevation and are bifurcated in plan and provided with the bevelled portions 1286 (Figure 34) adapted to engage the bevelled portion 1288 of the sleeves 1290, said sleeves being non-rotatably mounted on the respective gear shafts and provided with the crown 1292 adapted to engage the corresponding crown 1294 provided on the respective gears such as the gear 1158.

It is understood that every shaft aligned with the respective keys is provided with the sleeves 1290 in order that the loose gears on said shafts in the various positions may be selectively connected to said shafts, it being seen that the single bayonet socket joint in each slide makes it impossible to operate more than one key in a bank to its innermost position where the respective gears are connected to the respective shafts. It will thus be seen that a sleeve is provided for the tenth bank on shafts 1030, 1024, 1016, 1036, 1042, 1048, 1054, 1060, 1074, 1086 and 1094 to selectively connect the gears 1098, 1096, 1106, 1108, 1110, 1112, 1114, 1116, 1118, 1120, 1022 to said shafts. In the units bank the shafts 1024, 1016, 1036, 1042, 1048, 1054, 1060, 1072, 1084 are provided with the sleeve 1290 in order to connect the gears 1128, 1130, 1132, 1134, 1136, 1138, 1140, 1142, 1144 to said shafts. In the tens bank the shafts 1016, 1042, 1054, 1074 are provided with the sleeve 1290 to connect the gears 1158, 1162, 1166, 1170, respectively, to said shafts upon operation of the respective keys. The springs 1296 normally urge said crowns 1292 and 1294 out of engagement so that when the key 1274, for example, as shown in Figure 34, is moved outwardly to release engagement between said key and the bevel 1288, the spring 1296 will disconnect the crowns to thereby disconnect the gear 1158 from the shaft 1016.

In order, then, to select the proper price, as for example, 44 1/4¢, as shown in Figures 37, 38 and 39, it is only necessary to move the locking bars 1276, 1262 and 1238 to a position to permit inward movement of the selected keys 1274, 1250 and 1216. Inward movement of said keys causes the members 1288 on the shafts 1094, 1084 and

- 1016 to be depressed against the respective springs 1296, to engage the crowns 1292 and 1294, making a connection between the selected gears on their shafts, namely, the gears 1122, 1138, and 1158 will be connected with the shafts 1094, 1054 and 1016, respectively, which will cause the other gears to operate as idlers to the differential, where the motion of the respective gears is added and taken off at 1212 to the distributor.
- 5 10 When the keys are in fully inwardly extended position the locking bars can be slid to fully engage the keys and retain them in locked position.

Price synchronizing mechanism—Figures 35 and 36

- 15 15 In fully engaged position the posted price is set up, for example, as shown in Figure 35. In this case the locking bar 1238 is pivotally connected at one end as at 1298, and at its opposite end as at 1300 to the arms 1302 and 1304 of the gear segments 1306 and 1308 pivotally mounted as at 1310 and 1312. The gear segments mesh with the gears 1314 and 1316 provided on the fractional daily price indicating wheels 1318 and 1320 pivotally mounted as at 1322 and 1324. The locking bar 1262 is pivotally connected as at 1326 and 1328 to the members 1330 and 1332 pivotally mounted as at 1334 and 1336 and provided with the gear segments 1338 and 1340 meshing with the gears 1342 and 1344 of the units daily price wheels 1346 and 1348 pivoted as at 1350 and 1352. The locking bar 1276 is pivotally connected as at 1354 and 1356 to the arms 1358 and 1360 of the gear segments 1362 and 1364 pivotally mounted as at 1366 and 1368, and meshing with the gears 1370 and 1372 of the tens daily price indicating wheels 1374 and 1376 pivoted as at 1378 and 1380. Thus it will be seen that movement of the locking bars 40 to fully retaining locking position with respect to the selected keys sets up or indicates the selected price.

- 45 In order to provide means for indicating the selected price at a remote point, the daily price numeral wheels may be provided with the spaced contacts 1382 such as are shown applied to the daily price wheel 1348 in Figure 36. The contacts are disposed in the proper relative position with respect to the numerals on said wheels and are arranged to operate distant solenoids to remotely set distant numeral wheels, it being understood that the numeral wheel 1348 is set by the gear segment 1332 as has already been described. When the zero positions are selected 55 by any of the keys it will be seen that inward movement of the zero keys 1214, 1242 or 1266 causes movement of the adjacent pawls 1124, 1146 or 1172 to lock the gears 1122, 1144 or 1170, thus locking the gear train to prevent any movement from that gear train being added to the differential.

- 60 It is to be understood that I do not wish to be limited by the exact embodiments of the device shown, which are merely by way of illustration and not limitation, as various and other forms of the device will of course be apparent to those skilled in the art without departing from the spirit of the invention or the scope of the claims.

- 70 70 What is claimed is:
1. In a variating mechanism, the combination of an operating shaft, a plurality of driving shafts disposed about a vertical axis and substantially equidistant therefrom, gear means 75 disposed on said driving shafts, certain of the

gear means being connected in a train and so proportioned that each of the driving shafts rotates at a predetermined rate, a connection between said operating shaft and said train, a first bank of selecting gears disposed above said gear means, said selecting gears being rotatably mounted on certain of said driving shafts and provided with clutch means, said selecting gears being connected in a selecting gear train, clutch members non-rotatably mounted on the driving shafts provided with said selecting gears and being adapted to move to engage said clutch means to selectively connect the selected of the selecting gears to its respective shaft, a second bank of selecting gears disposed above said first bank of selecting gears, said selecting gears of said second bank being rotatably mounted on certain of said driving shafts and provided with clutch means, said second bank of selecting gears being connected in a second selecting gear train, clutch members non-rotatably mounted on the driving shafts provided with said second bank of selecting gears and being adapted to move to engage said second named clutch means to selectively connect the selected gear of the second bank of selecting gears to its respective shaft, a driven shaft, differential means connecting said gear trains to said driven shaft whereby said driven shaft will rotate in accordance with the selected of said selecting gears, rotatable selecting rings for each of said selecting trains encasing said trains and positioned by said driving shafts to rotate about said vertical axis, said rings each being provided with a flange for carrying said clutch members in declutched position, a portion of each of said flanges being provided with inclined planes defining an interrupted portion of said flange, said inclined planes causing selected downward movement of a selected clutch member to cause said clutch member to be moved to clutched position with respect to its adjacent selecting gear or causing upward movement of a selected clutch member to declutched position, a pivoted member carried by said flange for overlying the clutch members when in clutched position to maintain said clutched position, releaseable locking means for locking said rings in selected position, said locking means selectively locking said selecting gear trains when said rings are in predetermined position, indicating means for showing the setting of said rings, and means connecting said rings and said indicating means whereby movement of said rings moves said indicating means.

2. In variating mechanism, the combination of an operating shaft, a plurality of driving shafts disposed about a vertical axis and substantially equidistant therefrom, gear means disposed on said driving shafts, certain of the gear means being connected in a train and so proportioned that each of the driving shafts rotates at a predetermined rate, a connection between said operating shaft and said train, a first bank of selecting gears disposed above said gear means, said selecting gears being rotatably mounted on certain of said driving shafts and provided with clutch means, said selecting gears being connected in a selecting gear train, clutch members non-rotatably mounted on the driving shafts provided with said selecting gears and being adapted to move to engage said clutch means to selectively connect the selected of the selecting gears to its respective shaft, a second bank of selecting gears disposed above said first bank of

selecting gears, said selecting gears of said second bank being rotatably mounted on certain of said driving shafts and provided with clutch means, said second bank of selecting gears being connected in a second selecting gear train, clutch members non-rotatably mounted on the driving shafts provided with said second bank of selecting gears and being adapted to move to engage said second named clutch means to selectively connect the selected gear of the second bank of selecting gears to its respective shaft, a driven shaft, differential means connecting said gear trains to said driven shaft whereby said driven shaft will rotate in accordance with the selected of said selecting gears, rotatable selecting rings for each of said selecting trains encasing said trains and positioned by said driving shafts to rotate about said vertical axis, said rings each being provided with a flange for carrying said clutch members in declutched position, a portion of each of said flanges being provided with inclined planes defining an interrupted portion of said flange, said inclined planes causing selected downward movement of a selected clutch member to cause said clutch member to be moved to clutched position with respect to its adjacent selecting gear or causing upward movement of a selected clutch member to declutched position, a pivoted member carried by said flange for overlaping the clutch members when in clutched position to maintain said clutched position, and reseaseable locking means for locking said rings in selected position, said locking means selectively locking said selecting gear trains when said rings are in predetermined position.

3. In variating mechanism, the combination of an operating shaft, a plurality of driving shafts disposed about a vertical axis and substantially equidistant therefrom, means interposed between 40 said operating and driving shafts whereby rotation of said operating shaft rotates said driving shafts, a first bank of selecting gears, said selecting gears being rotatably mounted on certain of said driving shafts and provided with clutch 45 means, said selecting gears being connected in a selecting gear train, clutch members non-rotatably mounted on the driving shafts provided with said selecting gears and being adapted to move to engage said clutch means to selectively connect 50 the selected of the selecting gears to its respective shaft, a second bank of selecting gears disposed above said first bank of selecting gears, said selecting gears of said second bank being rotatably mounted on certain of said driving shafts and provided with clutch means, said second bank of 55 selecting gears being connected in a second selecting gear train, clutch members non-rotatably mounted on the driving shafts provided with said second bank of selecting gears and being adapted to move to engage said second named clutch 60 means to selectively connect the selected gear of the second bank of selecting gears to its respective shaft, a driven shaft, differential means connecting said gear trains to said driven shaft 65 whereby said driven shaft will rotate in accordance with the selected of said selecting gears, rotatable selecting rings for each of said selecting trains encasing said trains and positioned by said driving shafts to rotate about said vertical axis, said rings each being provided with a flange 0 for carrying said clutch members in declutched position, a portion of each of said flanges being provided with inclined planes defining an interrupted portion of said flange, said inclined planes 5 causing selected downward movement of a se-

lected clutch member to cause said clutch member to be moved to clutched position with respect to its adjacent selecting gear or causing upward movement of a selected clutch member to de-clutched position, a pivoted member carried by said flange for overlying the clutch members when in clutched position to maintain said clutched position, and releaseable locking means for locking said rings in selected position, said locking means selectively locking said selecting gear trains when said rings are in predetermined position.

4. In variating mechanism, the combination of an operating shaft, a plurality of driving shafts disposed about a vertical axis and substantially equidistant therefrom, gear means disposed on said driving shafts, certain of the gear means being connected in a train and so proportioned that each of the driving shafts rotates at a predetermined rate, a connection between said operating shaft and said train, a first bank of selecting gears disposed above said gear means, said selecting gears being rotatably mounted on certain of said driving shafts and provided with clutch means, said selecting gears being connected in a selecting gear train, clutch members non-rotatably mounted on the driving shafts provided with said selecting gears and being adapted to move to engage said clutch means to selectively connect the selected of the selecting gears to its respective shaft, a second bank of selecting gears disposed above said first bank of selecting gears, said selecting gears of said second bank being rotatably mounted on certain of said driving shafts and provided with clutch means, said second bank of selecting gears being connected in a second selecting gear train, clutch members non-rotatably mounted on the driving shafts provided with said second bank of selecting gears and being adapted to move to engage said second named clutch means to selectively connect the selected gear of the second bank of selecting gears to its respective shaft, a driven shaft, differential means connecting said gear trains to said driven shaft whereby said driven shaft will rotate in accordance with the selected of said selecting gears, rotatable selecting means for each of said selecting trains, said means being so constructed and arranged that when one clutch member in a bank is in clutched position, the others in said bank are in de-clutched position, and releaseable locking means for said selecting means for locking said selecting means in selected position, said locking means selectively locking said selecting gear trains and said selecting means when said selecting means are in a predetermined position and said clutch members are declutched.

5. In variating mechanism, the combination of an operating shaft, a plurality of driving shafts disposed about a vertical axis and substantially equidistant therefrom, means interposed between said operating and driving shafts whereby rotation of said operating shaft rotates said driving shafts, a first bank of selecting gears, said selecting gears being rotatably mounted on certain of said driving shafts and provided with clutch means, said selecting gears being connected in a selecting gear train, clutch members non-rotatably mounted on the driving shafts provided with said selecting gears and being adapted to move to engage said clutch means to selectively connect the selected of the selecting gears to its respective shaft, a second bank of selecting gears disposed above said first bank of selecting gears, said selecting gears of said second bank being

5 rotatably mounted on certain of said driving shafts and provided with clutch means, said second bank of selecting gears being connected in a second selecting gear train, clutch members non-rotatably mounted on the driving shafts provided with said second bank of selecting gears and being adapted to move to engage said second named clutch means to selectively connect the selected gear of the second bank of selecting gears to its respective shaft, a driven shaft, differential means connecting said gear trains to said driven shaft whereby said driven shaft will rotate in accordance with the selected of said selecting gears, rotatable selecting means for each of said selecting trains, said means being so constructed and arranged that when one clutch member in a bank is in clutched position, the others in said bank are in de-clutched position, and releaseable locking means for said selecting means for locking said selecting means in selected position, said locking means selectively locking said selecting gear trains and said selecting means when said selecting means are in a predetermined position and said clutch members are declutched.

10 6. In variating mechanism, the combination of a driving shaft, a gear train driven by said shaft, intermediate shafts driven by certain of the gears of said train at predetermined speeds, gears rotatably mounted on said intermediate shafts, means for selectively connecting any of said last named gears to its respective shaft, means for selectively arresting movement of any of said last named gears, a driven member driven by the selected gears when connected to their respective shaft, and differential means operatively connecting said driven member to said selected gears.

15 7. In variating mechanism, the combination of a driving shaft, a gear train driven by said shaft, intermediate shafts driven by certain of the gears of said train at predetermined speeds, gears rotatably mounted on said intermediate shafts, certain of said last named gears being arranged in predetermined trains, a normally disconnected releaseable connection between said last named gears and their respective shafts, selecting members for selectively operating said connections whereby said driving shaft drives a portion of the first gear train to drive the selected shaft or shafts to thereby cause the selected shaft or shafts to

20 30 35 40 45 50 55

drive a portion of the second named gear trains from the selected gears, driven means driven by said portions of the second named gear trains, and differential means operatively connecting said driven means to said second named gear trains.

8. In variating mechanism, the combination of a driving shaft, a driven shaft, supplemental shafts, a gear train connecting said driving shaft and supplemental shafts, the gears of said gear train being arranged in a predetermined ratio, a plurality of banks of gears rotatably mounted on certain of said shafts, the gears in each bank being of a predetermined ratio and in mesh in a predetermined sequence, differential mechanism for connecting certain gears of said banks to said driven shaft, means for selectively connecting certain of the gears of said banks of gears to the associated intermediate shafts, locking means operable to render each of said banks inoperative, selecting members for operating the means for connecting the gears to said intermediate shafts or the locking means, and selecting member locking means for locking said selecting members in selected position and for preventing the move-

ment of more than one selecting member in a bank.

9. In variating mechanism, the combination of a driving shaft, a driven shaft, supplemental shafts, a gear train connecting said driving shaft and supplemental shafts, the gears of said gear train being arranged in a predetermined ratio, a plurality of banks of gears rotatably mounted on certain of said shafts, the gears in each bank being of a predetermined ratio and in mesh in a predetermined sequence, differential mechanism for connecting certain gears of said banks to said driven shaft, means for selectively connecting certain of the gears of said banks of gears to the associated intermediate shafts, locking means operable to render each of said banks inoperative, selecting members for operating the means for connecting the gears to said intermediate shafts or the locking means, selecting member locking means for locking said selecting members in selected position and for preventing the movement of more than one selecting member in a bank, and indicating means for showing the selection of a gear or locking means in a bank, said indicating means being operated by said selecting member locking means.

10. In variating mechanism, the combination of a driving shaft, a driven shaft, supplemental shafts, a gear train connecting said driving shaft and supplemental shafts, the gears of said gear train being arranged in a predetermined ratio, a plurality of banks of gears rotatably mounted on certain of said shafts, the gears in each bank being of a predetermined ratio and in mesh in a predetermined sequence, differential mechanism for connecting certain gears of said banks to said driven shaft, means for selectively connecting certain of the gears of said banks of gears to the associated intermediate shafts, locking means operable to render each of said banks inoperative, selecting members for operating the means for connecting the gears to said intermediate shafts or the locking means, selecting member locking means for locking said selecting members in selected position and for preventing the movement of more than one selecting member in a bank, indicating means for showing the selection of a gear or locking means in a bank, said indicating means being operated by said selecting member locking means, remote indicating means for showing said selection, and operative connections between said first and remote indicating means whereby both show the same indications.

11. In variating mechanism, the combination of operating mechanism, driving gears connected in a train, connecting means between said operating mechanism and driving gears, parallelly arranged shafts for said driving gears, said driving gears being non-rotatably mounted on the respective shafts, a first bank of selecting gears connected in a train, said selecting gears being rotatably mounted on certain of the respective shafts, normally declutched clutching means for connecting said selecting gears to the respective shafts, a second bank of selecting gears connected in a train, said last named selecting gears being rotatably mounted on certain of the respective shafts, normally declutched clutching means for connecting said last named selecting gears to their respective shafts, driven means, differential means connecting said driven means to said banks of selecting gears, and slideable members for each selecting gear movable to operate said clutching means to clutched position.

12. In variating mechanism, the combination of operating mechanism, driving gears connected in a train, connecting means between said operating mechanism and driving gears, parallelly arranged shafts for said driving gears, said driving gears being non-rotatably mounted on the respective shafts, a first bank of selecting gears connected in a train, said selecting gears being rotatably mounted on certain of the respective shafts, normally declutched clutching means for connecting said selecting gears to the respective shafts, a second bank of selecting gears connected in a train, said last named selecting gears being rotatably mounted on certain of the respective shafts, normally declutched clutching means for connecting said last named selecting gears to their respective shafts, driven means, differential means connecting said driven means to said banks of selecting gears, slideable members for each selecting gear movable to operate said clutching means to clutched position, and means for preventing more than one of said slideable members in each bank from being moved to clutched position.

13. In variating mechanism, the combination of operating mechanism, driving gears connected in a train, connecting means between said operating mechanism and driving gears, parallelly arranged shafts for said driving gears, said driving gears being non-rotatably mounted on the respective shafts, a first bank of selecting gears connected in a train, said selecting gears being rotatably mounted on certain of the respective shafts, normally declutched clutching means for connecting said selecting gears to the respective shafts, a second bank of selecting gears connected in a train, said last named selecting gears being rotatably mounted on certain of the respective shafts, normally declutched clutching means for connecting said last named selecting gears to their respective shafts, driven means, differential means connecting said driven means to said banks of selecting gears, slideable members for each selecting gear movable to operate said clutching means to clutched position, and means for locking all but one of said slideable members in clutch open position.

14. In variating mechanism, the combination of operating mechanism, driving gears connected in a train, connecting means between said operating mechanism and driving gears, parallelly arranged shafts for said driving gears, said driving gears being non-rotatably mounted on the respective shafts, a first bank of selecting gears connected in a train, said selecting gears being rotatably mounted on certain of the respective shafts, normally declutched clutching means for connecting said selecting gears to the respective shafts, a second bank of selecting gears connected in a train, said last named selecting gears being rotatably mounted on certain of the respective shafts, normally declutched clutching means for connecting said last named selecting gears to their respective shafts, driven means, differential means connecting said driven means to said banks of selecting gears, slideable members for each selecting gear movable to operate said clutching means to clutched position, and a movable member for each of said banks of selecting gears, each of said movable members having a portion movable to register with a slideable member to permit said slideable member to be moved to clutched position.

15. In variating mechanism, the combination of operating mechanism, a plurality of shafts,

the axes of said shafts being parallel, means connecting said operating mechanism and shafts for rotating said shafts in a predetermined manner, a first bank of selecting gears connected in a train, said selecting gears being rotatably mounted on certain of the respective shafts, normally declutched clutching means for connecting said selecting gears to the respective shafts, a second bank of selecting gears connected in a train, said last named selecting gears being rotatably mounted on certain of the respective shafts, normally declutched clutching means for connecting said last named selecting gears to their respective shafts, driven means, differential means connecting said driven means to said banks of selecting gears, and slideable members for each selecting gear movable to operate said clutching means to clutched position.

16. In variating mechanism, the combination of operating mechanism, a plurality of shafts, the axes of said shafts being parallel, means connecting said operating mechanism and shafts for rotating said shafts in a predetermined manner, a first bank of selecting gears connected in a train, said selecting gears being rotatably mounted on certain of the respective shafts, normally declutched clutching means for connecting said selecting gears to the respective shafts, a second bank of selecting gears connected in a train, said last named selecting gears being rotatably mounted on certain of the respective shafts, normally declutched clutching means for connecting said last named selecting gears to their respective shafts, driven means, differential means connecting said driven means to said banks of selecting gears, slideable members for each selecting gear movable to operate said clutching means to clutched position, and means for preventing more than one of said slideable members in each bank from being moved to clutched position.

17. In variating mechanism, the combination of operating mechanism, a plurality of shafts, the axes of said shafts being parallel, means connecting said operating mechanism and shafts for rotating said shafts in a predetermined manner, a first bank of selecting gears connected in a train, said selecting gears being rotatably mounted on certain of the respective shafts, normally declutched clutching means for connecting said selecting gears to the respective shafts, a second bank of selecting gears connected in a train, said last named selecting gears being rotatably mounted on certain of the respective shafts, normally declutched clutching means for connecting said last named selecting gears to their respective shafts, driven means, differential means connecting said driven means to said banks of selecting gears, slideable members for each selecting gear movable to operate said clutching means to clutched position, and means for locking all but one of said slideable members in clutch open position.

18. In variating mechanism, the combination of operating mechanism, a plurality of shafts, the axes of said shafts being parallel, means connecting said operating mechanism and shafts for rotating said shafts in a predetermined manner, a first bank of selecting gears connected in a train, said selecting gears being rotatably mounted on certain of the respective shafts, normally declutched clutching means for connecting said selecting gears to the respective shafts, a second bank of selecting gears connected in a train, said last named selecting gears being rotatably

mounted on certain of the respective shafts, normally declutched clutching means for connecting said last named selecting gears to their respective shafts, driven means, differential means connecting said driven means to said banks of selecting gears, slideable members for each selecting gear movable to operate said clutching means to clutched position, a movable member for each of said banks of selecting gears, each of said movable members having a portion movable to register with a slideable member to permit said slideable member to be moved to clutched position.

19. In variating mechanism, the combination of operating mechanism, driving gears connected in a train, connecting means between said operating mechanism and driving gears, parallelly arranged shafts for said driving gears, said driving gears being non-rotatably mounted on the respective shafts, a first bank of selecting gears connected in a train, said selecting gears being rotatably mounted on certain of the respective shafts, normally declutched clutching means for connecting said selecting gears to the respective shafts, a second bank of selecting gears connected in a train, said last named selecting gears being rotatably mounted on certain of the respective shafts, normally declutched clutching means for connecting said last named selecting gears to their respective shafts, driven means, differential means connecting said driven means to said banks of selecting gears, slideable members for each selecting gear movable to operate said clutching means to clutched position, means associated with each bank of selecting gears movable to lock said bank against rotation, and a slideable member for moving said last named means to lock the selected bank of selecting gears.

20. In variating mechanism, the combination of operating mechanism, driving gears connected in a train, connecting means between said operating mechanism and driving gears, parallelly arranged shafts for said driving gears, said driving gears being non-rotatably mounted on the respective shafts, a first bank of selecting gears connected in a train, said selecting gears being rotatably mounted on certain of the respective shafts, normally declutched clutching means for connecting said selecting gears to the respective shafts, a second bank of selecting gears connected in a train, said last named selecting gears being rotatably mounted on certain of the respective shafts, normally declutched clutching means for connecting said last named selecting gears to their respective shafts, driven means, differential means connecting said driven means to said banks of selecting gears, slideable members for each selecting gear movable to operate said clutching means to clutched position, means associated with each bank of selecting gears movable to lock said bank against rotation, a slideable member for moving said last named means to lock the selected bank of selecting gears, and means for preventing more than one of said slideable members in each bank from being moved to clutched position.

21. In variating mechanism, the combination of operating mechanism, driving gears connected in a train, connecting means between said operating mechanism and driving gears, parallelly arranged shafts for said driving gears, said driving gears being non-rotatably mounted on the respective shafts, a first bank of selecting gears connected in a train, said selecting gears being rotatably mounted on certain of the respective

shafts, normally declutched clutching means for connecting said selecting gears to the respective shafts, a second bank of selecting gears connected in a train, said last named selecting gears being rotatably mounted on certain of the respective shafts, normally declutched clutching means for connecting said last named selecting gears to their respective shafts, driven means, differential means connecting said driven means to said banks of selecting gears, slidable members for each selecting gear movable to operate said clutching means to clutched position, means associated with each bank of selecting gears movable to lock said bank against rotation, a slidale member for moving said last named means to lock the selected bank of selecting gears, and means for locking all but one of said slidable members in inoperative position.

22. In variating mechanism, the combination of operating mechanism, driving gears connected in a train, connecting means between said operating mechanism and driving gears, parallelly arranged shafts for said driving gears, said driving gears being non-rotatably mounted on the respective shafts, a first bank of selecting gears connected in a train, said selecting gears being rotatably mounted on certain of the respective shafts, normally declutched clutching means for connecting said selecting gears to the respective shafts, a second bank of selecting gears connected in a train, said last named selecting gears being rotatably mounted on certain of the respective shafts, normally declutched clutching means for connecting said last named selecting gears to their respective shafts, driven means, differential means connecting said driven means to said banks of selecting gears, slidable members for each selecting gear movable to operate said clutching means to clutched position, means associated with each bank of selecting gears movable to lock said bank against rotation, a slidale member for moving said last named means to lock the selected bank of selecting gears, a movable member for each of said banks of selecting gears, each of said movable members having a portion movable to register with a slidale member to permit said slidale member to be moved to operative position.

23. In variating mechanism, the combination of operating mechanism, a plurality of shafts, the axes of said shafts being parallel, means connecting said operating mechanism and shafts for rotating said shafts in a predetermined manner, a first bank of selecting gears connected in a train, said selecting gears being rotatably mounted on certain of the respective shafts, normally declutched clutching means for connecting said selecting gears to the respective shafts, a second bank of selecting gears connected in a train, said last named selecting gears being rotatably mounted on certain of the respective shafts, normally declutched clutching means for connecting said last named selecting gears to their respective shafts, driven means, differential means connecting said driven means to said banks of selecting gears, slidable members for each selecting gear movable to operate said clutching means to clutched position, means associated with each bank of selecting gears movable to lock said bank against rotation, and a slidale member for moving said last named means to lock the selected bank of selecting gears.

24. In variating mechanism, the combination of operating mechanism, a plurality of shafts, the axes of said shafts being parallel, means connect-

ing said operating mechanism and shafts for rotating said shafts in a predetermined manner, a first bank of selecting gears connected in a train, said selecting gears being rotatably mounted on certain of the respective shafts, normally declutched clutching means for connecting said selecting gears to the respective shafts, a second bank of selecting gears connected in a train, said last named selecting gears being rotatably mounted on certain of the respective shafts, normally declutched clutching means for connecting said last named selecting gears to their respective shafts, driven means, differential means connecting said driven means to said banks of selecting gears, slidable members for each selecting gear movable to operate said clutching means to clutched position, means associated with each bank of selecting gears movable to lock said bank against rotation, a slidale member for moving said last named means to lock the selected bank of selecting gears, and means for preventing more than one of said slidable members in each bank from being moved to operative position.

25. In variating mechanism, the combination of operating mechanism, a plurality of shafts, the axes of said shafts being parallel, means connecting said operating mechanism and shafts for rotating said shafts in a predetermined manner, a first bank of selecting gears connected in a train, said selecting gears being rotatably mounted on certain of the respective shafts, normally declutched clutching means for connecting said selecting gears to the respective shafts, a second bank of selecting gears connected in a train, said last named selecting gears being rotatably mounted on certain of the respective shafts, normally declutched clutching means for connecting said last named selecting gears to their respective shafts, driven means, differential means connecting said driven means to said banks of selecting gears, slidable members for each selecting gear movable to operate said clutching means to clutched position, means associated with each bank of selecting gears movable to lock said bank against rotation, a slidale member for moving said last named means to lock the selected bank of selecting gears, and means for locking all but one of said slidable members in inoperative position.

26. In variating mechanism, the combination of operating mechanism, a plurality of shafts, the axes of said shafts being parallel, means connecting said operating mechanism and shafts for rotating said shafts in a predetermined manner, a first bank of selecting gears connected in a train, said selecting gears being rotatably mounted on certain of the respective shafts, normally declutched clutching means for connecting said selecting gears to the respective shafts, a second bank of selecting gears connected in a train, said last named selecting gears being rotatably mounted on certain of the respective shafts, normally declutched clutching means for connecting said last named selecting gears to their respective shafts, driven means, differential means connecting said driven means to said banks of selecting gears, slidable members for each selecting gear movable to operate said clutching means to clutched position, means associated with each bank of selecting gears movable to lock said bank against rotation, a slidale member for moving said last named means to lock the selected bank of selecting gears, and a movable member for each of said banks of selecting gears, each of said movable members having a portion movable to

register with a slidable member to permit said slidable member to be moved to operative position.

27. In variating mechanism, the combination of an operating shaft, a plurality of driving shafts disposed about a vertical axis and substantially equidistant therefrom, gear means disposed on said driving shafts, certain of the gear means being connected in a train and so proportioned that each of the driving shafts rotates at a predetermined rate, a connection between said operating shaft and said train, a first bank of selecting gears, said selecting gears being rotatably mounted on certain of said driving shafts and provided with clutch means, said selecting gears being connected in a selecting gear train, clutch members non-rotatably mounted on the driving shafts provided with said selecting gears and being adapted to move to engage said clutch means to selectively connect the selected of the selecting gears to its respective shaft, a second bank of selecting gears, said selecting gears of said second bank being rotatably mounted on certain of said driving shafts and provided with clutch means, said second bank of selecting gears being connected in a second selecting gear train, clutch members non-rotatably mounted on the driving shafts provided with said second bank of selecting gears and being adapted to move to engage said second named clutch means to selectively connect the selected gear of the second bank of selecting gears to its respective shaft, a driven shaft, differential means connecting said gear trains to said driven shaft whereby said driven shaft will rotate in accordance with the selected of said selecting gears, said selecting gears for each of said selecting trains encasing said trains and positioned by said driving shafts to rotate about said vertical axis, said rings each being provided with a flange for carrying said clutch members in declutched position, a portion of each of said flanges being provided with inclined planes defining an interrupted portion of said flange, said inclined planes causing selected downward movement of a selected clutch member to cause said clutch member to be moved to clutched position with respect to its adjacent selecting gear or causing upward movement of a selected clutch member to declutched position, a pivoted member carried by said flange for overlying the clutch members when in clutched position to maintain said clutched position, and releaseable locking means for locking said rings in selected position, said locking means selectively locking said selecting gear trains when said rings are in predetermined position.

28. In variating mechanism, the combination of an operating shaft, a plurality of driving shafts disposed about a vertical axis and substantially equidistant therefrom, means interposed between said operating and driving shafts whereby rotation of said operating shaft rotates said driving shafts, a first bank of selecting gears, said selecting gears being rotatably mounted on certain of said driving shafts and provided with clutch means, said selecting gears being connected in a selecting gear train, clutch members non-rotatably mounted on the driving shafts provided with said selecting gears and being adapted to move to engage said clutch means to selectively connect the selected of the selecting gears to its respective shaft, a second bank of selecting gears, said selecting gears of said second bank being rotatably mounted on certain of said driving shafts and provided with clutch means, said second bank of selecting gears

being connected in a second selecting gear train, clutch members non-rotatably mounted on the driving shafts provided with said second bank of selecting gears and being adapted to move to engage said second named clutch means to selectively connect the selected gear of the second bank of selecting gears to its respective shaft, a driven shaft, differential means connecting said gear trains to said driven shaft whereby said driven shaft will rotate in accordance with the selected of said selecting gears, rotatable selecting rings for each of said selecting trains encasing said trains and positioned by said driving shafts to rotate about said vertical axis, said rings each being provided with a flange for carrying said clutch members in declutched position, a portion of each of said flanges being provided with inclined planes defining an interrupted portion of said flange, said inclined planes causing selected downward movement of a selected clutch member to cause said clutch member to be moved to clutched position with respect to its adjacent selecting gear or causing upward movement of a selected clutch member to declutched position, a pivoted member carried by said flange for overlying the clutch members when in clutched position to maintain said clutched position, and releaseable locking means for locking said rings in selected position, said locking means selectively locking said selecting gear trains when said rings are in predetermined position.

29. In variating mechanism, the combination of an operating shaft, a plurality of driving shafts disposed about a vertical axis and substantially equidistant therefrom, gear means disposed on said driving shafts, certain of the gear means being connected in a train and so proportioned that each of the driving shafts rotates at a predetermined rate, a connection between said operating shaft and said train, a first bank of selecting gears, said selecting gears being rotatably mounted on certain of said driving shafts and provided with clutch means, said selecting gears being connected in a selecting gear train, clutch members non-rotatably mounted on the driving shafts provided with said selecting gears and being adapted to move to engage said clutch means to selectively connect the selected of the selecting gears to its respective shaft, a second bank of selecting gears, said selecting gears of said second bank being rotatably mounted on certain of said driving shafts and provided with clutch means, said second bank of selecting gears being connected in a second selecting gear train, clutch members non-rotatably mounted on the driving shafts provided with said second bank of selecting gears and being adapted to move to engage said second named clutch means to selectively connect the selected gear of the second bank of selecting gears to its respective shaft, a driven shaft, differential means connecting said gear trains to said driven shaft whereby said driven shaft will rotate in accordance with the selected of said selecting gears, rotatable selecting means for each of said selecting trains, said means being so constructed and arranged that when one clutch member in a bank is in clutched position, the others in said bank are in declutched position, and releaseable locking means for said selecting means for locking said selecting means in selected position, said locking means selectively locking said selecting gear trains and said selecting means when said se-

lecting means are in a predetermined position and said clutch members are declutched.

30. In variating mechanism, the combination of an operating shaft, a plurality of driving shafts disposed about a vertical axis and substantially equidistant therefrom, means interposed between said operating and driving shafts whereby rotation of said operating shaft rotates said driving shafts, a first bank of selecting gears, said selecting gears being rotatably mounted on certain of said driving shafts and provided with clutch means, said selecting gears being connected in a selecting gear train, clutch members non-rotatably mounted on the driving shafts provided with said selecting gears and being adapted to move to engage said clutch means to selectively connect the selected of the selecting gears to its respective shaft, a second bank of selecting gears, said selecting gears of said second bank being rotatably mounted on certain of said driving shafts and provided with clutch means, said second bank of selecting gears being connected in a second selecting gear train, clutch members non-rotatably mounted on the driving shafts provided with said second bank of selecting gears and being adapted to move to engage said second named clutch means to selectively connect the selected gear of the second bank of selecting gears to its respective shaft, a driven shaft, differential means connecting said gear trains to said driven shaft whereby said driven shaft will rotate in accordance with the selected of said selecting gears, rotatable selecting means for each of said selecting trains, said means being so constructed and arranged that when one clutch member in a bank is in clutched position, the others in said bank are in declutched position, and releasable locking means for said selecting means for locking said selecting means in selected position, said locking means selectively locking said selecting gear trains and said selecting means when said selecting means are in a predetermined position and said clutch members are declutched.

31. In variating mechanism, the combination of an operating shaft, a plurality of driving shafts disposed about a vertical axis and substantially equidistant therefrom, means interposed between said operating and driving shafts whereby rotation of said operating shaft rotates said driving shafts, a first bank of selecting gears, said selecting gears being rotatably mounted on certain of said driving shafts and provided with clutch means, said selecting gears being connected in a selecting gear train, clutch members non-rotatably mounted on the driving shafts provided with said selecting gears and being adapted to move to engage said clutch means to selectively connect the selected of the selecting gears to its respective shaft, a second bank of selecting gears, said selecting gears of said second bank being rotatably mounted on certain of said driving shafts and provided with clutch means, said second bank of selecting gears being connected in a second selecting gear train, clutch members non-rotatably mounted on the driving shafts provided with said second bank of selecting gears and being adapted to move to engage said second named clutch means to selectively connect the selected gear of the second bank of selecting gears to its respective shaft, a driven shaft, differential means connecting said gear trains to said driven shaft whereby said driven shaft will rotate in accordance with the selected of said selecting gears, rotatable selecting rings for each of said selecting trains of said selecting means for each of said selecting trains encasing said trains and positioned by said driving shafts to rotate about said vertical axis, said rings each being provided with means moving a selected clutch member to clutched position with respect to its adjacent selecting gear or causing upward movement of a selected clutch member.

32. In variating mechanism, the combination of an operating shaft, a plurality of driving shafts disposed about a vertical axis and substantially equidistant therefrom, means interposed between said operating and driving shafts whereby rotation of said operating shaft rotates said driving shafts, a first bank of selecting gears, said selecting gears being rotatably mounted on certain of said driving shafts and provided with clutch means, said selecting gears being connected in a selecting gear train, clutch members non-rotatably mounted on the driving shafts provided with said selecting gears and being adapted to move to engage said clutch means to selectively connect the selected of the selecting gears to its respective shaft, a second bank of selecting gears, said selecting gears of said second bank being rotatably mounted on certain of said driving shafts and provided with clutch means, said second bank of selecting gears being connected in a second selecting gear train, clutch members non-rotatably mounted on the driving shafts provided with said second bank of selecting gears and being adapted to move to engage said second named clutch means to selectively connect the selected gear of the second bank of selecting gears to its respective shaft, a driven shaft, differential means connecting said gear trains to said driven shaft whereby said driven shaft will rotate in accordance with the selected of said selecting gears, rotatable selecting rings for each of said selecting trains encasing said trains and positioned by said driving shafts to rotate about said vertical axis, said rings each being provided with means moving a selected clutch member to clutched position with respect to its adjacent selecting gear or causing upward movement of a selected clutch member, and releasable locking means for locking said rings in selected position, said locking means selectively locking said selecting gear trains when said rings are in predetermined position.

33. In variating mechanism, the combination of operating mechanism, a plurality of shafts, the axes of said shafts being parallel, means connecting said operating mechanism and shafts for rotating said shafts in a predetermined manner, a first bank of selecting gears connected in a train, said selecting gears being rotatably mounted on certain of the respective shafts, normally declutched clutching means for connecting said selecting gears to the respective shafts, a second bank of selecting gears connected in a train, said last named selecting gears being rotatably mounted on certain of the respective shafts, normally declutched clutching means for connecting said last named selecting gears to their respective shafts, driven means, differential means connecting said driven means to said banks of selecting gears, slid able members for each selecting gear movable to operate said clutching means to clutched position, means associated with each bank of selecting gears movable to lock said bank against rotation, a slideable member for moving said last named means to lock the selected bank of selecting gears, means for preventing more than one of said

slidable members in each bank from being moved to operative position, and indicating means for showing the setting of said slidable members, said indicating means including numeral wheels, oscillatable members for moving said numeral wheels, and a connection between the respective oscillatable members and said slidable members.

34. In variating mechanism, the combination of operating mechanism, a plurality of shafts, the axes of said shafts being parallel, means connecting said operating mechanism and shafts for rotating said shafts in a predetermined manner, a first bank of selecting gears connected in a train, said selecting gears being rotatably mounted on certain of the respective shafts, normally declutched clutching means for connecting said selecting gears to the respective shafts, a second bank of selecting gears connected in a train, said last named selecting gears being rotatably mounted on certain of the respective shafts, normally declutched clutching means for connecting said last named selecting gears to their respective shafts, driven means, differential means connecting said driven means to said banks of selecting gears, slidable members for each selecting gear movable to operate said clutching means to clutched position, means associated with each bank of selecting gears movable to lock said bank against rotation, a slidable member for moving said last named means to lock the selected bank of selecting gears, means for preventing more than one of said slidable members in each bank from being moved to operative position, indicating means for showing the setting of said slidable members, said indicating means including numeral wheels, oscillatable members for moving said numeral wheels, a connection between the respective oscillatable members and said slidable members, remote indicating means, and electrical connections between said indicating means.

35. In combination, a train of driving gears, driven gears rotatably mounted with respect to said driving gears and disposed to constantly engage in driven trains, rotation of any gear of said driven trains rotating the remaining gears of said trains in a predetermined manner, means for selectively connecting certain of said driven gears to certain of said driving gears without disconnecting the gears of said trains, whereby the selected of said driven gears drives the remainder of said driven gears in the respective trains in accordance with the rotation of its respective driving gear, driven means, and means connecting said trains to said driven means whereby said driven means is given the resulting movement of said trains.

36. In combination, driving means, driven means, a train of constantly meshed driving gears driven by said driving means, shafts rotatable by said driving gears, a train of constantly meshed selecting gears, said gears being rotatably mounted on certain of said shafts, a second train of constantly meshed selecting gears, said last named gears being rotatably mounted on certain of said shafts, means for selectively connecting a selecting gear of each train to the associated shaft, and means connecting said gear trains to said driven means whereby said driving means drives said driven means through a portion of said driving gears and the selected selecting gears.

37. In combination, driving means, driven means, a train of driving gears driven by said

driving means, shafts rotatable by said driving gears, a train of selecting gears, said gears being rotatably mounted on certain of said shafts, a second train of selecting gears, said last named gears being rotatably mounted on certain of said shafts, means for selectively connecting a selecting gear of each train to the associated shaft, and means connecting said gear trains to said driven means whereby said driving means drives said driven means through a portion of said driving gears and the selected selecting gears.

38. In variating mechanism, the combination of a drive shaft, a train of constantly meshed driving gears connected to said drive shaft, shafts rotatable with said driving gears, a plurality of sets of selecting gears rotatably mounted on certain of said shafts, the driving gears in each set being constantly in mesh, a driven shaft, differential means connecting the driving gears of each set to said driven shaft whereby the effective movements from the selected gear of each set is transmitted to said driven shaft, means for connecting the selected of said selecting gears in each set to the shaft on which it is mounted, and means operative when said last named means is in a predetermined position for preventing movement of the associated set of selecting gears.

39. In variating mechanism, the combination of driven shafts, means for simultaneously driving said shafts in a predetermined ratio, selecting gears on said shafts adapted to be driven thereby, differential mechanism, means for causing the selected of said selecting gears to drive said differential mechanism or for arresting movement of a portion of said differential mechanism while said driven shafts are rotating, and means driven by said differential mechanism in accordance with the operation of the differential mechanism.

40. In variating mechanism, the combination of driven shafts, means for simultaneously driving said shafts in a predetermined ratio, selecting gears on said shafts adapted to be driven thereby, differential mechanism, means for causing the selected of said selecting gears to drive said differential mechanism or for arresting movement of a portion of said differential mechanism while said driven shafts are rotating, said last named means including linearly movable selecting members, and means driven by said differential mechanism in accordance with the operation of the differential mechanism.

41. In variating mechanism, the combination of rotatable shafts, means for simultaneously driving said shafts in a predetermined ratio, selecting gears on said shafts adapted to be driven thereby, differential mechanism, means for causing the selected of said selecting gears to drive said differential mechanism or for arresting movement of a portion of said differential mechanism while said rotatable shafts are rotating, said last named means including rotatable selecting members, and means driven by said differential mechanism in accordance with the operation of the differential mechanism.

42. In variating mechanism, the combination of rotatable shafts, means for simultaneously driving said shafts in a predetermined ratio, selecting gears on said shafts adapted to be driven thereby, differential mechanism, means for causing the selected of said selecting gears to drive said differential mechanism or for arresting movement of a portion of said differential mechanism while said rotatable shafts are rotating, said last named means including rotatable select-

ing members, means driven by said differential mechanism in accordance with the operation of the differential mechanism, indicating mechanism for showing the setting of said selecting members, said indicating mechanism including numeral wheels arranged to rotate about parallel axes, said axes being parallel to the axis of said selecting members, resilient means tending to return said numeral wheels to a predetermined position, and flexible means disposed between said selecting members and the corresponding numeral wheels.

43. In variating mechanism, the combination of rotatable shafts, means for simultaneously driving said shafts in a predetermined ratio, selecting gears on said shafts adapted to be driven thereby, differential mechanism, means for causing the selected of said selecting gears to drive said differential mechanism or for arresting movement of a portion of said differential mechanism while said rotatable shafts are rotating, said last named means including rotatable selecting members, means driven by said differential mechanism in accordance with the operation of the differential mechanism, indicating mechanism for showing the setting of said selecting members, said indicating mechanism including numeral

wheels arranged to rotate about a common axis, resilient means tending to return said numeral wheels to a predetermined position, and flexible means disposed between said selecting members and the corresponding numeral wheels.

- 5 44. In variating mechanism, the combination of rotatable shafts, means for simultaneously driving said shafts in a predetermined ratio, selecting gears on said shafts adapted to be driven thereby, differential mechanism, means for causing the selected of said selecting gears to drive said differential mechanism or for arresting movement of a portion of said differential mechanism while said rotatable shafts are rotating, said last named means including rotatable selecting members, means driven by said differential mechanism in accordance with the operation of the differential mechanism, indicating mechanism for showing the setting of said selecting members, said indicating mechanism including numeral wheels arranged to rotate about parallel axes, said axes being parallel to the axis of said selecting members, and continuous flexible means disposed around portions of said selecting members and the corresponding numeral wheels.

KENLY C. BUGG.
